[57] CLAIM

The ornamental design for a combined housing, blade irons and switch housing unit for a ceiling, as shown and described.

DESCRIPTION

FIG. 1 is a perspective view of a combined housing, blade irons and switch housing unit for a ceiling fan showing my new design, the broken lines being illustrative of environmental structure only and forming no part of the claimed design;

FIG. 2 is a additional perspective view of the combined housing, blade irons and switch housing unit for a ceiling fan shown in FIG. 1;

FIG. 3 is a front view of the combined housing, blade irons and switch housing unit for a ceiling fan shown in FIG. 2;

FIG. 4 is a right-side view thereof;

FIG. 5 is a rear view thereof;

FIG. 6 is a left-side view thereof;

FIG. 7 is a top view thereof; and,

FIG. 8 is a bottom view thereof.
